UNITED STATES PATENT OFFICE.

ROBESON B. WOLCOTT, OF EAST CLEVELAND, OHIO, ASSIGNOR TO RALPH S. MUELLER,
OF CLEVELAND, OHIO.

ATTACHMENT-PLUG.

1,224,987.

Specification of Letters Patent.

Patented May 8, 1917.

Application filed August 30, 1915. Serial No. 48,067.

To all whom it may concern:

Be it known that I, ROBESON B. WOLCOTT, a citizen of the United States, residing at East Cleveland, in the county of 5 Cuyahoga and State of Ohio, have invented certain new and useful Improvements in Attachment-Plugs, of which the following is a specification.

My invention relates to attachment plugs 10 such as are used for connecting electric extension cords or wires to lamp or other receptacles for the purpose of conducting current to portable translating devices, lamps, motors, heating devices, etc.

The principal object of my invention is to 15 provide an attachment plug which can be readily wired. I am aware that various forms of attachment plugs have been proposed and are in use, but in all those plugs 20 with which I am familiar, it is difficult and therefore expensive to wire them. In some of the attachment plugs now in use, the wires are connected to the terminals by screws, which, besides being so small as to 25 make their manipulation extremely difficult by wiremen whose fingers are clumsy from performing heavy work, are liable to become loosened in service and permit the stranded wires to make short circuits, thus 30 causing fuses to melt, or more serious trouble. In other plugs with which I am familiar, the wires are soldered to metal parts which, in turn, are electrically connected to the terminals of the plug. These 35 devices are expensive to manufacture and are also difficult to wire.

Another object of my invention is to provide an attachment which can be easily manufactured at low cost, there being but 40 four separate parts, all of which are extremely simple.

Still another object of my invention is to provide an attachment plug in which the wire connections are made by soldering the 45 wires to their terminals, a form of connection which is conceded by all electricians to be the safest and most efficient.

I attain these and other objects, and avoid the objectionable features of other forms of

attachment plugs by the use of the device 50 illustrated in the accompanying drawings in which:

Figure 1 is an end view and Fig. 2 is a longitudinal section of one form of my invention; Fig. 3 is an end view and Fig. 4 55 is a longitudinal section of a modified form of my invention; and Fig. 5 is a side elevation of my invention.

In the drawings, 1 represents an ordinary Edison lamp base, made up of the oval 60 threaded, metal shell, 2, which forms one terminal of the circuit, the center metallic contact disk, 3, and the insulation, 4, which is molded about and firmly secures the parts, 2 and 3, together, so that, mechanically speaking, they form a single member. 5 represents the main body of the attachment plug which is preferably made of insulating material which can be molded 65 separately from the lamp base and afterward assembled therein. 6 and 7 are the wires which are connected respectively to the terminals, 2 and 3, and conduct current where desired. Wires 6 and 7 are 70 shown twisted together in the form of the ordinary stranded duplex conductor or lamp cord commonly used for such purposes. The contact disk, 3, has a hole, 8, at its center. One of the conductors, 7, is 75 passed through this hole and soldered to the disk from the outside as clearly shown in the drawing. When the conductor is stranded, the strands may be spread apart outside of the hole, and, when soldered, form a substantial button which cannot be 80 pulled through the hole, 8.

The main body, 5, of the plug is threaded at 9 to receive the metal shell, 2. At the outer end of the body, 5, there is an enlarged portion, 10, the outer surface of 90 which may be knurled or fluted to facilitate manipulation when the device is being screwed into or out of a lamp socket or other receptacle.

A hole, 11, extends longitudinally through 95 the body, 5, for the reception of the conductors leading to the terminals of the plug.

In the form of attachment plug shown

in Figs. 1 and 2 a transverse slot, 12, is formed diametrically across the end of the body, 5, and from either end of this slot a longitudinal slot, 13, extends to the shoulder, 14, of the enlargement, 10. Joining slot, 13, a radial slot, 15, may be formed in the shoulder, 14, to facilitate the soldering of the conductor, 6, to the shell, 2, at the point 16 as shown in Fig. 2.

- 10 The shell, 2, is preferably indented at 16 to firmly contact with the conductor wire, before soldering, and to form a lock or key to prevent the subsequent unscrewing of the shell from the body, 5. The opposite side 15 of the shell may be indented at 16^a into the vacant slot, 13, on that side, to form an additional lock against such unscrewing.

In the form of attachment plug shown in Figs. 3 and 4 there is a central longitudinal hole, 17, which extends through the body, 18. Instead of making hole, 17, of uniform size, I prefer to form a shoulder, 19, and contract the diameter of the hole beyond this shoulder as shown at 17^a. In this form 25 the slot, 12, is not shown, although it could be made in the end of the body without detriment and thereby enable the plug to be wired either as shown in Fig. 2, or as shown in Fig. 4. On opposite sides of hole 17 and 30 cutting partly into the shoulder, 19, partly through the wall of the hole, 17, are holes, 20, extending obliquely through the material of the body, 18, and connecting with slots, 21, which are similarly located to 35 slots, 13, of Fig. 2.

The conductor to be connected to the shell, 2, may be passed through either of slots, 20, and soldered as at 22, the shell, 2, being indented at 22 and 22^a similar to the 40 indentations at 16, 16^a of Fig. 2.

It will be understood that the indentations, 16, 16^a or 22, 22^a, are not to be made until the wires have been placed and the shell, 2, has been screwed on to the body of 45 the plug. To wire the plug the shell is separated from the body, the wires are passed through the body and the insulation is removed from the wires for a short distance back from the ends. The ends of 50 the wires are then bent into the approximate positions they are to occupy when connected to the plug and the base, 1, is screwed in place. The center conductor, 7, readily passes through the hole, 8, on account of the funnel shaped or counter-sunk opening, 23, in the insulation, 4, while the conductor which is to be connected to the shell is pressed into the slot, 13, or 21, and retained there by the shell as the latter is 55 screwed on to the body of the plug. After the base, 1, is in place the shell, 2, is indented as described and the ends of the conductor are soldered to their respective terminals. It will be observed that when 60

the shell is bent into the groove, it not only 65 locks the base in the shell against independent turning, but also tends to clamp the end of the conductor wire in the groove so that when the solder is applied a very efficient electrical connection is made. 70

My preferred form of attachment plug is shown in section in Fig. 2. In this form, it is to be noted that one of the conductor wires passes clear through the central longitudinal hole, 11, of the body portion, 5, 75 is bent outward over the end of the body, backward through the longitudinal slot, 13, and again outward in the radial slot, 15, where it is soldered to the inner end of the threaded shell, 2. This bending of one of 80 the conductors over the end of the body materially adds to the ability of the conductors to withstand excessive pulls upon them without becoming detached from the attachment plug terminals. That conductor which is connected to the metal shell in the manner described, will resist such pulls and protect the other conductor from excessive pulls.

Other modes of applying the principles 90 of my invention may be employed without departing from its scope.

I claim as my invention:—

1. An attachment plug for electric circuits comprising a cylindrical metal shell 95 having internal and external threads formed thereon, a metal contact disk at one end of said shell insulated therefrom and secured thereto, said disk having an aperture therethrough adapted to receive a conductor wire, a cylindrical body of insulating material threaded externally to fit the internal thread of said shell and having a central longitudinal hole therethrough and an external longitudinal groove along one side, said groove being covered by said shell, said longitudinal hole being adapted to receive the two conductor wires which are attached to the plug, one of which wires enters said hole, extends through said body, passes through said aperture in said disk and is electrically connected thereto, and the other of which wires enters said hole, extends first through said body, then radially outward and then backward through said external longitudinal groove and is electrically connected to said shell at its outer end. 100 105 110 115

2. In an attachment plug for electric conductors, the combination with a body of non-conducting material having an externally threaded shank, an enlarged portion forming a transverse shoulder on said shank, a central longitudinal hole extending through said body adapted to receive two conductor wires, an external longitudinal slot in said shank extending from the end of said shank to said shoulder and a 120 125

- transverse slot in said shank intersecting said longitudinal slot and extending outward therefrom, said slots being adapted to receive a conductor wire, of a metal shell 5 provided with internal and external threads, a metal contact disk, insulating material electrically separating and mechanically joining said disk to one end of said shell in axial alinement therewith, 10 said disk and said insulating material each having a central longitudinal hole through it adapted to receive a conductor wire, said shell and said disk constituting the electric terminals of the attachment plug and being 15 adapted to make contact with the terminals of an incandescent electric lamp socket, said shell being adapted to be screwed onto said shank.
3. In an attachment plug for electric conductors, the combination with a body of non-conducting material having an externally threaded shank, an enlarged portion forming a transverse shoulder on said shank, a central longitudinal hole extending 20 through said body adapted to receive two conductor wires, an external longitudinal slot in said shank extending from the end of said shank to said shoulder and a transverse slot in said shank intersecting said longitudinal slot and extending outward therefrom, said slots being adapted to receive a conductor wire, of a metal shell provided with internal and external threads, 25 a metal contact disk, insulating material electrically separating and mechanically joining said disk to one end of said shell in axial alinement therewith, said disk and said insulating material each having a central longitudinal hole through it adapted to receive a conductor wire, said shell and said disk constituting the electric terminals of the attachment plug, and being adapted to make contact with the terminals of an incandescent electric lamp socket, said shell 30 being adapted to be screwed onto said shank, and two conductor wires, one of them being passed through said central longitudinal holes in said body, said insulating material and said disk and soldered to said disk, and the other being passed through said central longitudinal hole in said body, bent outward over the end of said shank and backward through said slots beneath said shell and soldered to said shell.
5. In an attachment plug for electric conductors, a body of non-conducting material having an externally threaded shank adapted to be screwed into the metal shell of an Edison incandescent electric lamp base, 40 an enlarged portion forming means for manipulating said attachment plug and forming a transverse shoulder to limit the distance said shank may enter said shell, a central longitudinal hole extending through 45 said body for the reception of the wires connected to the attachment plug and an external longitudinal slot extending from end to end of said threaded shank, terminating at said shoulder, adapted to receive that one of said wires which is to be connected to 50 said shell.
5. An attachment plug comprising an insulating body having a threaded shank; a shell screwed onto the shank; a contact member insulated from the shell, said shank 55 having an inner longitudinal passageway extending therethrough and an external groove which at its outer end leads into or communicates with said longitudinal passageway.
6. In combination, an attachment plug comprising an insulating body having a shank provided with a longitudinal passageway extending therethrough and provided with an external groove; a contact member 60 engaging the outer surface of the shank and covering said groove; a second contact member insulated from the first named and located adjacent the outer end of the passageway; and two conductors both extending 65 through said passageway toward the outer end of the plug, and one extending from the longitudinal passageway to and then back along said external groove and electrically connected to said first named contact member, and the other electrically connected to said second named contact member.
7. In combination, a plug comprising an insulating body having a shank provided with a longitudinal passageway and with a transverse slot or groove at its outer end; a shell surrounding said shank; a substantially centrally disposed contact member near the outer end of said longitudinal passageway and insulated from the shell; and two conductors, both extending through said longitudinal passageway, one electrically connected to the contact member and the other extending from said longitudinal passageway through the transverse groove 100 and electrically connected to the shell.
8. An attachment plug for electric circuits comprising a cylindrical metal shell having internal and external threads formed thereon, a metal contact disk at one end of said shell insulated therefrom and secured thereto, said disk having an aperture therethrough adapted to receive a conductor wire, a cylindrical body of insulating material threaded externally to fit the internal 105 thread of said shell and having a central longitudinal hole therethrough, an external longitudinal groove along one side, and a transverse groove at its end connecting the central longitudinal hole with the external groove, said longitudinal groove being covered by said shell, said longitudinal hole being adapted to receive the two 110

conductor wires which are attached to the plug, one of which wires enters said hole, extends through said body, passes through said aperture in said disk and is electrically connected thereto, and the other of which wires enters said hole, extends first through said body, then radially outward through the transverse groove and then backward through said external longitudinal groove

and is electrically connected to said shell at 10 its outer end.

In testimony whereof I affix my signature in presence of two witnesses.

ROBESON B. WOLCOTT.
